UNITED STATES PATENT OFFICE.

JAMES W. TAVENNER, OF BLOOMINGTON, ILLINOIS.

DESIGN FOR A GAME-BOARD.

SPECIFICATION forming part of Design No. 35,118, dated September 17, 1901.

Application filed August 19, 1901. Serial No. 72,610. Term of patent 7 years.

To all whom it may concern:

Be it known that I, JAMES W. TAVENNER, a citizen of the United States, residing at Bloomington, in the county of McLean and State of Illinois, have invented and produced a certain new and original Design for a Game-Board; and I do declare the following to be a full, clear, and exact description of the invention, such as will enable others skilled in the art to which it appertains to make and use the same.

The invention relates to a new and original design for a game-board; and it consists of the design of the configuration and ornamentation shown in the accompanying drawings, in which—

Figure 1 is a perspective view of the obverse side of the board, and Fig. 2 is a similar view of the reverse side of the board.

The leading feature of the design comprises a rectangular board 1, provided with a marginal flange 2, the edges of which project above and below the upper and lower surfaces of the board, the obverse side of the board having at its corners recesses 3, a double-line annulus 4, a checkered center panel 5, upon which are outlined concentric stars 6 and 6', and horizontal rows of small stars 9, the star

6' being arranged within the star 6, a border 6² for the checkered panel, consisting of a rectangular row of triangular figures, an approximately rectangular straight figure 10, radiating lines 10^a, radiating checkered lines 10^b, and a rectangular figure 10^c, cutting at a tangent the annulus 4 at eight points. The reverse side of the board has a central rectangular raised panel 11', the edges of which, in conjunction with the annular flange of the board, form a groove or ditch 12, and the face of which is provided with concentric rings 13 and a central pocket 14 and with upwardly-projecting posts 16. Four lines 17 radiate from the center ring and extend to the corners of the raised panel.

What I claim is—

The design for a game-board, as herein shown and described.

In testimony whereof I have hereunto set my hand in presence of two subscribing witnesses.

JAMES W. TAVENNER.
